UNITED STATES PATENT OFFICE

166,372

EXPANSIBLE CHAIN FOR A WRIST WATCH BRACELET OR THE LIKE

William C. Boots, Rumford, R. I., assignor to
Foster Metal Products Incorporated, Attleboro,
Mass., a corporation of Massachusetts

Application October 20, 1951, Serial No. 17,059
Term of patent 14 years

(Cl. D45—4)

To all whom it may concern:

Be it known that I, William C. Boots, a citizen of the United States, residing at Rumford, in the county of Providence and State of Rhode Island, have invented a new, original, and ornamental Design for an Expansible Chain for a Wrist Watch Bracelet or the like, of which the following is a specification, reference being had to the accompanying drawing, forming a part thereof, in which:

Fig. 1 is a plan view of a major portion of an expansible chain for a wrist watch bracelet, showing my new design, represented in contracted position,

Fig. 2 is a view corresponding to Fig. 1 representing the chain in slightly expanded condition, and

Fig. 3 is a view corresponding to Fig. 2 in elevation, the under links being shown conventionally in dotted lines.

The dominant features of the design reside in the portions shown in full lines.

I claim:

The ornamental design for an expansible chain for a wrist watch bracelet or the like, substantially as shown and described.

WILLIAM C. BOOTS.
